UNITED STATES PATENT OFFICE.

CHARLES M. PHILLIPS AND CHARLES M. ROYER, OF MIDDLEBRANCH, OHIO.

RAILWAY-TIE.

No. 882,906.

Specification of Letters Patent. Patented March 24, 1908.

Application filed April 29, 1907. Serial No. 370,988.

To all whom it may concern:

Be it known that we, CHARLES M. PHILLIPS and CHARLES M. ROYER, citizens of the United States, residing at Middlebranch, in 5 the county of Stark and State of Ohio, have jointly invented certain new and useful Improvements in Railway-Ties; and we do hereby declare that the following is a full, clear, and exact description of the same, reference 10 being had to the accompanying drawing, making a part of this specification, and to the numerals and figures of reference marked thereon, in which:—

Figure 1 is a perspective view showing a 15 number of ties placed in proper relative position, also showing rails placed thereon. Fig. 2 is a longitudinal section of the tie showing transverse sections of the rails and the rails properly connected to the tie. Fig. 3 is a detached perspective view showing different parts of the tie detached from each other.

The present invention has relation to railway ties, and it consists in the novel arrangement hereinafter described and particularly 25 pointed out in the claims.

Similar numerals of reference indicate corresponding parts in all the figures of the drawing.

In the accompanying drawing, 1 represents the tie proper, which consists of a 30 channel bar preferably formed of sheet steel, and of the desired strength for the purpose intended. Within the channel bar 1 are located the rail supporting blocks 2, which 35 rail supporting blocks are formed of sufficient length to properly support the rails 3. The blocks 2 should be formed of such a length that they will not only support the railway rails 3, but of a length sufficient to 40 properly attach the rails to the block and the blocks to the bar, as hereinafter described, without danger of splitting the blocks. The blocks are connected to the bar 1 by means of spikes 5, which spikes are of the same kind 45 and practically one-half the size of the spikes 6 used for connecting the railway rails to the block.

It is of great importance to provide means to prevent any spreading of the rails, and 50 in order to prevent any movement of the blocks in an outward direction the angled end members 7 are provided, which angled end members are securely bolted or riveted to the side members of the channel bar 1, 55 thereby providing an abutment for the outer ends of the block 2, so that the strength of

the metal will be utilized in preventing any spreading of the railway rails and the strain removed from the spikes 5, which spikes are driven into the side faces of the blocks 2. 60

For the purpose of providing for proper drainage the channel bars 1 or ties proper are provided with the openings 8, which openings are preferably located as shown in the drawings, and as shown one opening 65 below each block and an intermediate opening between the blocks.

It will be understood that by providing the blocks 2 and forming the same of wood the same advantages are carried out as to 70 elasticity wherein the entire tie is formed of wood but by providing the blocks a great reduction, is brought about as to the use of wood.

It will be understood that the blocks 2 75 should extend a short distance above the channel bars or ties 1 so that the railway rails will not come in contact with the top or upper edges of the channel bars 1. By providing the short angled end members 7 and 80 locating them at the outer ends of the block 2 it is not necessary to cut the blocks to exact length and in new work it is not necessary to remove any of the metal parts when it is desired to insert the blocks, but in repair work 85 where the rails have already been laid the end members 7 may be removed and the blocks slid under the rails after which said end members are securely connected by means of the bolts or rivets as the case may be. 90

For the purpose of clamping the wood blocks 2, so that there can be no movement endwise in either direction regardless of the side spikes 5 the inner angled flange members 9 are provided which inner angled 95 flanges are adjustably connected to the channel bar or tie 1 by means of the slots 10 formed in the side members of the slots or channel bars 1.

It will be understood that by providing 100 the angled flanges 9, said angled flanges need not necessarily be removed, but the bolts 11 can be loosened and the angled members 9 adjusted back and forth so as to provide proper contact upon the inner ends of the 105 blocks in case they vary in length. After the blocks have been placed in position the angled members 9 are snugly seated against their inner ends and the clamping bolts 11 tightened.

Having fully described our invention, what 110 we claim as new and desire to secure by Letters Patent, is—

In a railway tie, the combination of a channel bar formed of metal, the vertical flanges of said bar provided with slots, rail-supporting blocks located between the vertical members of the channel bar and extended above said vertical flanges, outer angled flange members secured in fixed position to the channel bar, inner angled flange members adjustably attached to said channel bar, and adapted to abut against the ends of said

5 rail-supporting blocks, substantially as and for the purpose specified.

In testimony that we claim the above, we have hereunto subscribed our names in the presence of two witnesses.

CHARLES M. PHILLIPS.
CHARLES M. ROYER.
